E. C. MCKINNIE,
SHADE HOLDER FOR LIGHTING FIXTURES,
APPLICATION FILED AUG. 21, 1919.

Patented June 28, 1921.

UNITED STATES PATENT OFFICE.

EARLE C. MCKINNIE, OF CHICAGO, ILLINOIS, ASSIGNOR TO NATIONAL X-RAY REFLECTOR CO., OF CHICAGO, ILLINOIS, A CORPORATION OF ILLINOIS.

SHADE-HOLDER FOR LIGHTING-FIXTURES.

1,382,661.

Specification of Letters Patent. Patented June 28, 1921.

Application filed August 21, 1919. Serial No. 318,850.

To all whom it may concern:

Be it known that I, EARLE C. MCKINNIE, a citizen of the United States, residing in the city of Chicago, county of Cook, and 5 State of Illinois, have invented a certain new and useful Improvement in Shade-Holders for Lighting-Fixtures, of which the following is the specification.

The object of my invention is to provide a 10 collapsible bowl holder for lighting fixtures, which will be of great advantage for shipping purposes, and which can be readily and easily set up and adjusted for use by an inexperienced person, and when in operative 15 position, will firmly and securely hold the bowl.

My invention consists of certain details of construction hereinafter set forth, pointed out in my claims and illustrated in the accompanying drawings, in which:

Figure 1 shows a side elevation view of my bowl holder secured to a bowl, a part of the bowl being broken away.

Fig. 2 shows a sectional view of a portion 25 of the socket, shell, ring, and a part of one of the arms I employ.

Fig. 3 shows a side elevation view of the collar or ring I employ.

Fig. 4 shows a detail view of the upper 30 portion of one of the arms I employ.

Fig. 5 shows a detail view of a modified form of my device in which a shell is not employed, the light socket performing the function of the shell.

35 Referring to the accompanying drawings, the reference numeral 10 is used to indicate the cylindrical shell attached to the end of an electric cord, chain hanger, or the like, said shell being slightly flared at its base, as 40 shown at 11. This shell is designed to receive an electric light socket 12, in the ordinary manner, so that contact will be made to close the circuit which will thereafter be controlled by the light switch. The numeral 45 13 indicates a collar or ring, designed to engage the outer surface of the shell at the base, said ring being provided with a plurality of channels or recesses 14 pressed outwardly from the inner surface of the ring, 50 said recesses terminating, at the upper extremity of the shoulder 15. In the wall of the shoulder I provide orifices 16 which are preferably T-shaped in conformation, located adjacent the upper extremity of the 55 recesses in the said collar.

The numerals 17 indicate arms preferably made of metal straps, their upper ends terminating in heads 18 with recesses thereunder, the construction being such that the heads 18 are adapted to protrude through 60 their respective T-shaped orifices in the collar, and to be secured therein by means of the shoulders on the T-shaped recesses passing through the recesses below the heads on the ends of the arms. The arms extend 65 downwardly from the collar, and thence outwardly at substantially right angles, their outer ends terminating in hooked members 19 to receive the outer edge of the bowl 20. Immediately above the point where the arms 70 flare outwardly, as described, I have provided a slight outward and inward bend 21, and a spring metal ring 22 surrounds the plurality of arms above the bend in the vertical portions thereof, said ring being designed to spring over the bends in the arms, and to be seated immediately above the outwardly flaring bends in the arms, when the arms have been secured to the bowl.

75 In practical operation, the collar with the arms loosely depending therefrom, is placed on the outer surface of the shell and moved downwardly to its seat near the base thereof. This straightens the loosely depending arms and holds them, to some extent, in position. 80 The socket is then pressed in position within the shell. At this time the metal clamping ring is surrounding the depending arms above the bends in the vertical portions thereof. The bowl is then placed in position, being grasped by the hook members on the outward ends of the arms, and the clamped ring is then forced downwardly over the outwardly and inwardly bending portions of the arms to its seat resting upon 85 the substantially horizontal part of the arms, as shown in Fig. 1. This firmly clamps the arms to the bowl.

90 It is obvious from this construction that the bowl will be firmly and securely held in 100 proper position by the arms and that my holder is collapsible so that it will occupy but small space for shipping purposes.

95 It is obvious that my device may be used on fixtures where a socket receiving shell is not employed, by causing the socket itself to perform the function of the shell as shown in Fig. 5, without varying my invention, the principal feature of which is to provide a 105 collar with loosely depending arms adapted 110

to be held in position by contact with the shell or the outer surface of a socket shell, the outer ends of the arms engaging the bowl, with means to hold the arms in position for such engagement.

Having thus described my invention, what I claim and desire to secure by Letters Patent of the United States, is:

1. A bowl holder for lighting fixtures comprising in combination a collar adapted to fit over the socket receiving shell, and channels in the collar; a plurality of arms depending from, and loosely secured within the channels in the collar, said arms extending downwardly in a substantially vertical plane and thence outwardly to the edge of the bowl and terminating in hooks to receive the bowl, an outwardly projecting shoulder formed in each arm above the point where it flares outwardly; a ring to encircle the

substantially vertical portions of the arms and designed to be forced downwardly over the outwardly projecting shoulders, substantially as shown and described.

2. A bowl holder for lighting fixtures comprising a shouldered collar adapted to fit over a light socket having a flange at its lower end on which said collar rests and a plurality of arms fitted to vertical channels formed in said collar and depending therefrom, said arms flaring outwardly to a point adjacent the edge of the bowl and means on said arms to secure the bowl thereto, a ring adapted to surround the arms and to be seated thereon so as to retain the arms in rigid position with the bowl, when secured thereto.

In testimony whereof I have signed the foregoing specification.

EARLE C. McKINNIE.
